Primary Examiner — Joseph Kukella*Assistant Examiner* — Heather Wencl(74) *Attorney, Agent, or Firm* — CANTOR COLBURN LLP(57) **CLAIM**

The ornamental design for an elevator screen as shown and described.

DESCRIPTION

FIG. 1 is a perspective view of an elevator screen showing our new design;

FIG. 2 is a front view thereof;

FIG. 3 is a back view thereof;

FIG. 4 is a top view thereof;

FIG. 5 is a bottom view thereof;

FIG. 6 is a side view thereof;

FIG. 7 is another side view thereof; and,

FIG. 8 is a perspective view thereof.

The broken lines in the drawings depict portions of the elevator screen that form no part of the claimed design.

1 Claim, 6 Drawing Sheets(56)
